INVENTOR
CHARLES F. PARKS.
BY Thomas L. Ryan
ATTORNEY.

UNITED STATES PATENT OFFICE.

CHARLES F. PARKS, OF FAIRMOUNT, INDIANA.

BOAT-PROPELLING DEVICE.

1,379,933.

Specification of Letters Patent. Patented May 31, 1921.

Application filed September 19, 1919. Serial No. 324,805.

To all whom it may concern:

Be it known that I, CHARLES F. PARKS, a citizen of the United States, residing at Fairmount, in the county of Grant and State 5 of Indiana, have invented certain new and useful Improvements in Boat-Propeller Devices, of which the following is a specification.

This invention relates to improvements in 10 rowing devices for skiffs or similar hand propelled boats.

The object of my invention is to provide a device which may easily be attached to any standard skiff or row boat, and by 15 which the person operating same may propel the boat with a minimum amount of exertion and may vary the direction of movement of the boat and even reverse such movement, without changing his position on the 20 boat.

More specific purposes of my invention are to provide a device of the kind described which will be of few parts, durable, not liable to get out of order or repair, and 25 which is economical of manufacture.

The objects of this invention are accomplished by the mechanism shown in the accompanying drawings, and described in the following specification. In the drawings, 30 suitable characters of reference are applied to the several parts of the invention, as they appear in the different views, in which—

Figure 1 is a transverse sectional view of an ordinary standard type of row boat, 35 upon which my invention is shown installed.

Fig. 2 is a side view of the invention as seen in the direction indicated by the arrow in Fig. 1.

Fig. 3 is an enlarged view of the device as 40 shown in Fig. 1, parts thereof being shown in cross section.

Fig. 4 is a top plan sectional view taken on the line 4—4, and Fig. 5 is a top plan 45 sectional view taken on the line 5—5 in Fig. 3.

The present invention contemplates the arrangement of a pair of hand operable levers journaled in suitable bearings that are secured on the sides of the boat; arms 50 being extended from the lower portions of said levers, and upon which arms, hinged collapsible blades are carried; (the function of the blades is to present resistance to the water so that when the levers are operated 55 the boat will be moved,) and the arrangement of connections between the blades

and the levers so that the operator may quickly and easily cause a reversal of the position of the blades with reference to the arms of the levers, so that the direction of travel of the boat may be controlled, modified, or even reversed, although the position of the oarsman is unchanged and the effort is simply that of the back and forth movement of the levers.

In the drawings A represents the body portion of an ordinary boat, it being provided with the usual top rails B. My rowing attachment comprises the parts as follows: the cast metal journal block 1 is designed and arranged to fit securely on the rail B and to be secured by a suitable bolt or bolts 1^a. The lever 2 of suitable length and form as shown has its lower end secured to a shaft 3 that is journaled in the journal-block 1. Integrally formed on the end of the shaft 3 is a housing 3^a in which is journaled the shank portion of the blade shaft 5. A gear wheel 6 that forms a part of the top end of the shaft 5 has its teeth to mesh 55 in a rack 7. This rack is slidingly retained in guideway 3^b, and its stem 7^a is similarly retained in the guideway 2^a. When the rack is shifted the distance of its stroke, there is the one-half of a full rotation of the shaft 85 5. The means for moving the rack comprises the secondary lever 8 suitably journaled on the lug 2^b of the lever 2. This secondary lever 8 has its lower end connected loosely by a pin 7^b to the rack 7.

As shown in Fig. 1, the length of the blade shafts 5 are such that when the lever 2 is at the vertical position, the lower end of the blades is at a position slightly higher than a line parallel with the keel point of the boat. The blades 5^a are made of sheet metal which may be of steel, copper or brass and are connected to the shaft 5 in the manner of a loose hinge. The detail of this construction is shown at Fig. 5, the pins 5^c being secured in the ears 5^b that form a part of the shafts 5. When collapsed, these blades swing loosely on the pins 5^c, the eyes 5^d being so formed with reference to the ears 5^b that when expanded to the position as shown in Fig. 1, they are at the limit of the open position. It will be understood that by means of a spring 4 which may be arranged between the secondary lever 8 and the lever 2, the several parts are retained

normally at the position shown, the rack 7 being at retracted position.

In operating the invention, when the lever 2 is pulled in the direction indicated by the 5 arrow in Fig. 2 the blades 5 occupy the open position, to resist the water, as shown; and when moved in the opposite direction the blades as they freely swing on their pin connections, to the collapsed position, 10 presented a minimum resistance to the water, in the reverse stroke of the levers 2.

By my invention a person may propel the boat with uniformly minimum exertion, and the operation of the boat is silent and 15 effective, the pulling on the levers being accompanied by a positive and regular grip of the water and propulsion of the boat, in the forward direction, as indicated by the arrow. To reverse the direction of movement of the boat the operator simply grips the handles 8^a of the secondary levers and which action causes an outward shift of the racks 7 and a consequent rotative movement 20 of the gear wheel 6 and shaft 5, and which reverses the position of the blades 5^a and of 25 their resistance to the water, thereby reversing the direction of movement of the boat. The utility of my improved propelling device is easily apparent when it is seen that 30 control of the direction of movement of the boat may be effectively and easily had by operating one or the other or both of the levers in the manner above described.

While I have shown the lever and blade 35 mechanisms of my invention arranged to occupy position vertical to the center line of the boat, it is apparent that these parts may be disposed at a slant or angle, and moreover that changes may be made in the details 40 of construction and arrangement, without

departing from the nature or spirit of my invention or sacrificing any of its advantages.

What I claim as my invention, and desire to secure by Letters Patent, is—

1. A rowing device, comprising a primary lever, a shaft to which the lever is secured, a journal bearing for the shaft, an arm journaled in the said shaft at an angle to the axis of said shaft, a secondary lever carried by the primary lever, connections between the arm and the said secondary lever that cause the said arm to be shifted rotatively a predetermined distance when the secondary lever is operated, blades collapsibly carried by the said arm adapted to assume a spread position of resistance to the water when the primary lever is moved in one direction, and to assume a collapsed position when the said lever is moved in the opposite direction. 60

2. A rowing device, comprising a primary lever, a shaft to which the lever is secured, a journal bearing for the shaft, an arm journaled in the shaft at an angle to the axis of the shaft, a secondary lever fulcrumed on the side of the primary lever, a spring to normally hold the weight arm of the secondary lever at retracted position, a pinion on the said arm, a rack to mesh in the pinion and having loose connection with 70 the weight arm of the secondary lever, blades collapsibly carried by the said arm adapted to assume spread position of resistance to the water when the primary lever is moved in one direction, and to assume a collapsed position when the said lever is moved in the opposite direction. 75

In testimony whereof I affix my signature.

CHARLES F. PARKS.
